(57) **CLAIM**

The ornamental design for a sensor housing for open door sensor, as shown and described.

DESCRIPTION

FIG. 1 is a front top right-side perspective view of the sensor housing for open door sensor of the present invention;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a bottom back left perspective view thereof.

1 Claim, 8 Drawing Sheets
